[57] CLAIM

The ornamental design for a cork screw opener, as shown and described.

DESCRIPTION

FIG. 1 is a front elevational view of a cork screw opener showing my new design, various components of the cork screw opener being shown in an operative configuration, the rear elevational view being a mirror image thereof;
FIG. 2 is a top plan view thereof;
FIG. 3 is a bottom plan view thereof;
FIG. 4 is a left end elevational view thereof;
FIG. 5 is a right end elevational view thereof; and,
FIG. 6 is a front elevational view of the cork screw opener with the various components thereof being shown in a stored configuration.

Fig. 2

Fig. 3

FIG. 5

FIG. 4

FIG. 6
